ALFRED D. ANTOINE AND FLOYD BLACK, OF CHICAGO, ILLINOIS, ASSIGNEES TO
ADVANCE MACHINE CO., OF CHICAGO, ILLINOIS, A CORPORATION OF ILLINOIS.

CHECK-CONTROLLED MACHINE.

1,210,882.

Specification of Letters Patent.

Patented Jan. 2, 1917.

Application filed August 5, 1916. Serial No. 113,240.

To all whom it may concern:

Be it known that we, ALFRED D. ANTOINE and FLOYD BLACK, citizens of the United States, residing at Chicago, in the county 5 of Cook and State of Illinois, have invented certain new and useful Improvements in Check-Controlled Machines, of which the following is a specification.

This invention relates to improvements 10 in check controlled machines and more particularly to machines of the type whereby the operator upon depositing a check of the proper character and manipulating the machine, will receive an electric 15 shock, the strength of which may be readily controlled by the operator through the degree of manipulation of the machine.

A further object is to provide improved 20 means whereby the check will be ejected to prevent a repetition of the operation of the machine by the same check.

A further object is to provide improved 25 means whereby the circuit will be automatically rendered inactive beyond a predetermined point in the strength of the circuit.

To the attainment of these ends and the accomplishment of other new and useful objects as will appear, the invention consists 30 in the features of novelty in substantially the construction, combination and arrangement of the several parts hereinafter more fully described and claimed, and shown in the accompanying drawings illustrating the invention and in which,

35 Figure 1 is a front elevation of a portion of a machine of this character constructed in accordance with the principles of this invention. Fig. 2 is a rear elevation of the parts shown in Fig. 1. Fig. 3 is a top plan view of the parts shown in Fig. 2. Fig. 4 is a vertical sectional view taken on line 4-4, Fig. 2. Fig. 5 is a diagrammatic view of the circuits.

Referring more particularly to the drawings, the numeral 10 designates a supporting 40 plate or member upon which all of the parts are mounted and this member is provided with a slot or opening 11 through which an indicating gage 12 is visible and over which 45 a hand or pointer 13 is adapted to be moved by the manipulation of a handle 14, in a manner to be hereinafter described,

and which handle 14 is arranged on the outside of the plate. Supported in any suitable manner and adjacent the rear of the plate 55 10 is a magnetic core 15 over which a sleeve 16 operates and this sleeve 16 is adapted to be moved lengthwise of the core to vary the magnetic field, through the medium of a bell crank lever 17, pivotally mounted as at 60 18, one end of the lever on one side of the pivot being connected by means of a link 19 with the sleeve 16, while the other end of the bell crank lever is connected by means of a link 20 to an arm 21, which in turn is 65 connected with the handle 14. The connection between the link 20 and the arm 21 is preferably a pin and slot connection 22, 23 to permit the handle 14 and the arm 21 to be moved a short distance before the arm 70 21 operates upon the link 20 to rock the bell crank lever 17. Thus it will be seen that when the handle 14 is moved, the sleeve 16 will be moved longitudinally of the core 15 and this movement will vary the magnetic 75 field. The pointer 13 is also connected with the bell crank 17 so that as the sleeve 16 is adjusted, the pointer 13 will be correspondingly moved over the graduations 12 to indicate the strength of the current. An elastic member 24 is provided and may be connected with the pointer 13 and also anchored to a fixed support, so that when the handle 14 is moved in one direction to shift the pointer 13, a stress will be exerted upon the 80 elastic member 24, so that when the handle 14 is released, the elastic member will tend to move the pointer back to zero position and also assist in shifting the sleeve 16.

The core 15 is provided with a primary 90 winding 25, one extremity of which winding is secured to a binding post 26, while the other extremity of the winding is secured to a binding post 27 and the binding post 26 is connected to one side of a battery 28 by 95 means of a conductor 29. A vibrator 30 is provided adjacent the end of the core 15 and an adjustable platinum point 31 cooperates with the vibrator. This platinum point 31 is connected by means of a conductor 32 100 with the other side of the battery 28. A secondary winding 33 surrounds the primary winding 25 and one end of the secondary winding is connected by means of a con-

ductor 34 with a handle 35 which is connected with and insulated from the plate 10. The other end of the secondary winding is connected with the binding post 27 to which 5 one end of the primary winding 25 is also connected and leading from this binding post 27 is a conductor 37 which is connected with spaced contacts 38. The vibrator 30 is connected with a metallic bracket 39 which 10 in turn is secured to the plate 10 and the handle 14 being mounted upon the plate 10 is also included within the circuit.

The plate 10 is provided with a coin receiving slot 40 through which a coin may be 15 deposited into a coin receiver 41, being delivered to the receiver 41 by means of a chute 42, arranged adjacent the opening 40.

The receiver 41 is provided with a recess or cutout portion 43 through which a portion 20 of a pivotally mounted shiftable contact 44 is adapted to pass when the handle 14 is operated and when there is no check seated in the check seat.

The shiftable contact 44 is pivotally 25 mounted as at 45 and is preferably in the form of a knife switch which is adapted to pass between the spaced spring contact members 38; when the member 44 is shifted in one direction against the stress of an elastic 30 member 46 and which elastic member tends to move the element 44 in the opposite direction when the handle is released or the check discharged in a manner to be set forth. A stop 47 may be provided for limiting the 35 movement of the member 44 under the influence of the elastic member 46.

When the member 44 is shifted to a position that the member will pass between and have engagement with the spring contacts 40 38, the circuit through the coils will be completed and the core 15 will be energized.

The circuit passes from the battery 28 through the conductor 29 to the binding post 26, thence through the primary winding 25 to the binding post 27, thence through 45 the conductor 37, contact 38, element 44, supporting plate 10, bracket 39, through the vibrator 30, platinum point 31, conductor 32 back to the battery 28.

50 At the same time a circuit will be established from the binding post 27 through the secondary winding 33, conductor 34, handle 35, through the ground to the handle 14.

The contact member 44 is adapted to be 55 shifted by means of the check when it is deposited in the check receptacle 41, as the check, when the handle 14 is moved, will contact with the element 44 and shift the latter between the spring contacts 38. At 60 the same time the shifting of the handle 14 will shift the sleeve 16 over the windings to vary the magnetic field, as will be understood, and the sleeve will be shifted over the non-conducting portion 48; the pointer 13

being connected with the lever 17, will also 65 be correspondingly moved over the graduations 12. An elastic member 49 may be provided for assisting in returning the check receptacle 41 and the handle 14.

In order to prevent the repetition of the 70 operation of the machine after it has been once operated when a check has been deposited in the machine, the member 44 is preferably provided with a series of steps or shoulders 50 arranged along that face 75 thereof over which the check is moved, so that when the check is advanced over the face, it will successively pass behind the shoulders 50, and these shoulders operate, when the handle 14 is released to eject the 80 check from the seat 41. The member 44 is also provided with a recess or cutout portion 51 opening through the same face thereof and this recess is adapted to receive the edge of the check to permit the member 44 to be 85 shifted by the elastic member 46, and thereby move the member 44 out of engagement or electrical connection with the spring contacts 38 when the handle 14, and the sleeve 16, have reached the limit of their shifting 90 movement in one direction. After the edge of the check has entered the recess 51, and when the handle 14 is released, the check will be ejected from the seat 41 and the handle will be returned to its normal position 95 by means of the elastic member 49.

With this improved construction it will be manifest that the slightest retrograde movement of the handle 14 after a check has been deposited in the seat 41 will result in 100 the ejection of the check from the check seat, and it will be further manifest that when the handle 14 and the pointer 13 have been shifted to their extreme positions, in which the full strength of the current will 105 be dispensed, the member 44 will be automatically shifted by the elastic member 46 to interrupt the circuit and thereby prevent injury.

Obviously any number of windings of the 110 primary and secondary coils may be provided, but in practice very satisfactory results have been obtained with two layers of windings for the primary coil and four layers of windings for the secondary coil. 115

If desired and in order to insure the proper positioning of the member 44 between the spring contacts 38, a guide 52 may be provided and over which guide the member 44 is adapted to move.

120 What is claimed as new is:

1. A machine of the character described embodying an electric circuit, a shiftable handle included in the circuit, a magnetic coil also included in the circuit, a check controlled make and break device for the circuit, said make and break device embodying a fixed contact, a shiftable contact movable

- into and out of engagement therewith, means tending normally to move the shiftable contact in a direction to render the circuit inactive, a check seat shiftable in one direction to move the check into engagement with the shiftable contact to shift the latter to render the circuit active, means whereby the first recited means will shift the contact at a predetermined point in the forward movement of the check in the check seat, and means whereby a retrograde movement of the check seat will shift the check with relation to its seat to render the circuit inactive.
- 15 2. A machine of the character described embodying an electric circuit, a shiftable handle included in the circuit, a magnetic coil also included in the circuit, a check controlled make and break device for the circuit, said make and break device embodying a fixed contact, a shiftable contact movable into and out of engagement therewith, means tending normally to move the shiftable contact in a direction to render the circuit inactive, a check seat shiftable in one direction to move the check into engagement with the shiftable contact to shift and hold the latter in engagement with the fixed contact, said shiftable contact movable out of engagement with the fixed contact when the check is shifted with respect to its seat, means whereby a retrograde movement of the check seat from any position to which it has been advanced will shift the check with relation to its seat to render the circuit inactive, and means whereby the movable contact may be moved out of engagement with the fixed contact when the check is in the seat.
- 30 3. A device of the character described embodying an electric circuit, a magnetic coil included in the circuit, means for varying the strength of the field of said coil, a make and break device for controlling the circuit, said make and break device embodying a fixed and a shiftable contact movable into and out of engagement therewith, means tending normally to separate said contacts, said shiftable contact being provided with spaced projections on one face, a check seat, means for moving the said seat to cause the check to successively move over the said projections, means for varying the strength of the said circuit, and means for rendering the circuit inactive while the check is in said seat.
- 45 4. A device of the character described embodying an electric circuit, a shiftable handle, a check controlled make and break device for the circuit and embodying coöperating contacts one of which is shiftable with respect to the other, a shiftable check seat, means for shifting the seat to move the check into engagement with one of the contacts to move the latter into operative posi-
- tion with the other contact, means responsive to the movement of the check for varying the strength of said circuit, and means whereby the circuit will be rendered inactive at a predetermined point in its strength and while the check is still in its seat.
- 50 5. A device of the character described embodying an electric circuit, a shiftable handle, a check controlled make and break device for the circuit and embodying coöperating contacts one of which is shiftable with respect to the other, a shiftable check seat, means for shifting the seat to move the check into engagement with one of the contacts to move the latter into operative position with the other contact, means responsive to the movement of the check for varying the strength of said circuit, and means whereby the check will be ejected from its seat upon a retrograde movement of the seat, and means whereby the circuit will be rendered inactive at a predetermined point in its strength and while the check is still in its seat.
- 55 6. A device of the character described embodying an electric circuit, a magnetic coil included in the circuit, means for varying the strength of the field of said coil, a make and break device for controlling the circuit, said make and break device embodying a fixed contact and a shiftable contact movable into and out of engagement therewith, means tending normally to separate said contacts, said shiftable contact being provided with spaced projections on one face, a check seat, and means for moving the said seat to cause the check to successively move over said projections to shift and hold the movable contact in engagement with the fixed contact, said projections operating to eject the check upon a retrograde movement of the check seat to permit the movable contact to be shifted to render the circuit inactive, and provisions whereby the movable contact may be shifted while the check is still in the seat, to render the circuit inactive.
- 60 7. A device of the character described embodying an electric circuit, a magnetic coil included in the circuit, means for varying the strength of the field of said coil, a make and break device for controlling the circuit, said make and break device embodying a fixed contact and a shiftable contact movable into and out of engagement therewith, means tending normally to separate said contacts, said shiftable contact being provided with spaced projections on one face, a check seat, and means for moving the said seat to cause the check to successively move over said projections to shift and hold the movable contact in engagement with the fixed contact, said projections operating to eject the check upon a retrograde movement of the check seat, to permit the movable contact to be shifted to render the circuit inactive.

tact to be shifted to render the circuit inactive, and provisions whereby the movable contact may be shifted while the check is still in the seat, to render the circuit inactive, the said provisions embodying a cut away portion in the shifttable contact to receive the edge of the check.

In testimony whereof we have signed our

names to this specification, in the presence of two subscribing witnesses, on this 19th day 10 of July, A. D. 1916.
